UNITED STATES PATENT OFFICE.

FRED RENCH, OF COLTON, CALIFORNIA.

PENHOLDER AND PENCIL ATTACHMENT.

SPECIFICATION forming part of Letters Patent No. 675,792, dated June 4, 1901.

Application filed October 12, 1900. Serial No. 32,878. (No model.)

To all whom it may concern:

Be it known that I, FRED RENCH, a citizen of the United States, residing at Colton, in the county of San Bernardino and State of California, have invented a new and useful Penholder and Pencil Attachment, of which the following is a specification.

My invention relates to penholder and pencil attachments, and has for its object to produce a device of this kind which can be quickly applied to different instruments and which will enable the pupil to assume the right position in writing and at the same time will give motion to a slow hand; and it consists in the improved construction and novel arrangement of parts of such attachment, as will be hereinafter more fully set forth.

In the accompanying drawings, forming a part of this specification, Figure 1 is a perspective view showing the manner of applying and using my improved attachment. Fig. 2 is a plan view of the attachment complete, and Figs. 3 and 4 are cross-sectional views through the opposite ends of the attachment.

My improved attachment consists of a substantially bow-shaped spring 1 of suitable material, preferably of light metal. The forward end of the spring is provided with two clamping-jaws 2, which are preferably curved in cross-section, and each of them has its free edge provided with a projecting lip or flange, through which is passed a clamping-screw 4. The opposite end of the spring is provided with a breast-button 5, which is swiveled or pivotally secured thereto in any suitable manner—as, for instance, by means of a screw 6. The screw passes through an opening 7, which is arranged transversely through the end of the spring.

In using my improved attachment the pen or pencil to which it is to be applied is slipped through the clamping-jaws 2 and rigidly secured therein by means of the clamping-screw 4. When the student grasps the pen or pencil in the hand to use it in the ordinary manner, the rear end of the bow will extend back far enough as to cause the button 5 to rest upon the breast and thereby to hold the pencil or pen at the proper angle when the pupil is sitting upright at the desk. In this posi-

tion the attention of the pupil can be given entirely to the formation of the letters without thought as to the proper position of the pen or pencil, which will be controlled or governed by the attachment, thereby permitting the student to make great progress and avoid the formation of incorrect habits in relation to the position of the body and of the instrument being used.

The spring preferably tapers gradually to the rear, so as to give perfect freedom of movement to the hand of the writer, and yet at the same time the forward end must possess sufficient strength and rigidity to prevent the instrument being forced into or held in an improper position.

Having thus fully described my invention, what I claim as new, and desire to secure by Letters Patent of the United States, is—

1. A device of the kind described, consisting of a bow-shaped spring, having a clamp at one end and a swiveled button at the opposite end, substantially as described.

2. An attachment for penholders comprising a substantially bow-shaped spring, the forward end of which is provided with two clamping-jaws, each having a perforated lip, a screw passing through said lips, and a breast-button at the rear end, substantially as described.

3. An attachment for penholders, comprising a substantially bow-shaped spring, the forward end of which is provided with means for securing it in position, and the rear end transversely perforated, a screw in said perforation and a button swiveled upon said screw, substantially as described.

4. An attachment for penholders comprising a substantially bow-shaped spring to be secured to the holder, the forward end of the spring being provided with two clamping-jaws curved in cross-section, each jaw being provided with a perforated lip, a clamping-screw through said perforations, and a breast-button swiveled to the rear end of said spring, substantially as described.

FRED RENCH.
